UNITED STATES PATENT OFFICE.

LE ROY YAKELEY, OF SYRACUSE, NEW YORK.

DESIGN FOR AN ARTIFICIAL BAIT.

49,378.

Specification for Design.

Patented July 11, 1916.

Application filed December 6, 1915. Serial No. 65,426. Term of patent 14 years.

To all whom it may concern:

Be it known that I, LE ROY YAKELEY, a citizen of the United States, residing at the city of Syracuse, in the county of Onondaga, in the State of New York, have invented a new, original, and ornamental Design for an Artificial Bait, of which the following is a specification, reference being had to the accompanying drawing, forming part thereof.

Figure 1 is a top plan, Fig. 2 a side eleva-

tion, and Fig. 3 a front end view of an artificial bait embodying my new design.

I claim:

The ornamental design for an artificial bait as shown.

LE ROY YAKELEY.
